(57) **CLAIM**

The ornamental design for a lawn mower as shown and described.

DESCRIPTION

FIG. 1 is a perspective view of a lawn mower, showing our new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top plan view of FIG. 1; and,

FIG. 7 is a bottom plan view of FIG. 1.

The broken lines shown in the drawings are for the purpose of illustrating portions of the lawn mower that form no part of the claimed design.

1 Claim, 7 Drawing Sheets(56)
